UNITED STATES PATENT OFFICE.

THEODOR VON DEYLEN, OF VISSELHÖVEDE, GERMANY.

PACKAGE FOR MATCHES.

969,045.

Specification of Letters Patent. Patented Aug. 30, 1910.

Application filed June 29, 1910. Serial No. 569,587.

To all whom it may concern:

Be it known that I, THEODOR VON DEYLEN, manufacturer, a subject of the King of Prussia, and resident of Visselhövede, Province of Hanover, Prussia, Germany, have invented new and useful Packages for Matches, of which the following is a specification.

This invention relates to the well-known, 10 folded pasteboard, thin packages for matches, and its novel feature consists in a special process of manufacturing such packages cheaply.

The invention is represented on the accompanying drawing, wherein:—

Figure 1 is a bottom plan of an unfolded strip of pasteboard without matches having a line of rupture incised therein, and Fig. 2 a like view with a perforated line of rupture; Fig. 3 shows the holder in perspective; Fig. 4 shows the arrangement of a holder in a pocket-receptacle after the folded flap has been torn off, Fig. 5 a filled package comprising three separate small 25 holders, while Fig. 6 shows the empty unfolded strips of pasteboard as seen from the outside, and Fig. 7 represents the manufacture of double packages.

The package consists, as is particularly 30 seen from Figs. 1 and 2, of simple rectangular strips of pasteboard and can consequently be cut without waste from sheets of pasteboard. The ends *a* of these strips are provided with a composition for igniting 35 the matches, while at the rupturing edge of the opposite end, at which the flap *d* is to be folded, a groove, preferably incised in the form of a line of rupture *b*, or perforation *c* is provided. In special instances two lines of rupture in this fold may 40 be incised or impressed at a definite distance. Likewise, if desired, a line of rupture or perforations *h* may be incised at the edge of the ignition surface. The applying 45 of the ignition composition on the one end *a* of the strip is very important, because not only is this flap stiffened thereby and the provision of closure slits and, correspondingly, the punching of tongues on 50 the opposite flap is rendered unnecessary, but in first place it enables a large number of packages to be provided in hundreds at once with igniting composition. For this 55 purpose the composition is applied before the sheets of pasteboard are cut into strips,

the individual sheets, from which the packages are cut, being superposed like roofing tiles in such manner that only the parts which are to be covered with the composition are exposed. In this manner 400 and 60 more packages can be covered with composition simultaneously, when 20 sheets of pasteboard, each of which when cut suffices for 20 individual packages, are superposed in the manner indicated.

The insertion of the matches and the folding over of the flap *d* is facilitated by the lines of rupture, because by simply folding the part *d* upward an abutment for the match heads is formed, so that the flap can be folded over and affixed by one single manipulation. In addition, the edge of rupture or its line enables the holder to have a suitable size after the separation of the flap *d*, in order to be able to put it at once into a suitable pocket-receptacle without using a knife or scissors (Fig. 3). The matches themselves are provided with an incised line of rupture *e*, while the receptacles have an up turned lip *f*, which holds the package down and acts like a cutting edge, under which lip the matches or the package is inserted. The line of rupture *e* and the height of the lip *f* are made to correspond with one another in order that the matches may break off at their line of fracture *e* and the adjacent matches remain uninjured. The flaps *d* are torn off, as indicated above, along the appertaining lines of rupture. In this manner, as will be understood from the above, the holder obtains its predetermined size for the purpose of its insertion into the pocket-receptacle. The dimensions are such that the edge of rupture *b* or *c* coincides as nearly as possible with the top edge *g* of the box and thus gives a certain hold to the package in the receptacle. The purpose of the abovementioned line of rupture *h* at the edge of the composition is for simplifying the latter being torn off when the same is to be employed in suitable match stands or holders.

Preferably a large number of connected holders, as illustrated by way of example in Figs. 5 and 6, is filled with matches and the holders are preferably provided at their place of separation with perforated lines *i*, so that the connected holders can be put on to the market. The consumer will then be able readily to separate one of the filled holders, as required, along the perforation *i*. In this

manner work is considerably facilitated both during the checking and during the despatch of the packages etc.

The strip of pasteboard adjoining the top portion *c* may be made symmetrically so that a double package is formed, as illustrated by way of example in Fig. 7.

It will be observed that the matches are inserted in the same manner as in the illustrative embodiments according to Figs. 1 10 and 2, while when the two halves are folded together along the edges *c* a double holder is obtained which is filled at both sides, each half being capable of being readily separated 15 along the perforation *c* and placed in the pocket-box.

I claim:—

A package for matches composed of a number of holders placed side by side and 20 made from a single piece of paste board and separated by weakened lines from each

other, each of said holders having a weakened line near one end and a plurality of weakened lines at the other end, the top part being adapted to fold down over the matches, 25 and the bottom part being adapted to fold up with its edge over the edge of the top part, an igniting composition being applied simultaneously to the outside of the bottom part of all the holders, thereby stiffening 30 the whole package while allowing the holders to be torn off in succession, substantially as described.

In testimony, that I claim the foregoing as my invention, I have signed my name in 35 presence of two witnesses.

THEODOR VON DEYLEN.
